Primary Examiner—Nelson C. Holtje*Attorney, Agent, or Firm*—Merchant, Gould, Smith, Edell, Welter & Schmidt[57] **CLAIM**

The ornamental design for a watch, as shown and described.

DESCRIPTION

FIG. 1 is a front perspective view of the watch;
FIG. 2 is an enlarged top plan view of the case and
watch face, the band portions having been omitted for
ease of illustration; and,
FIG. 3 is a back perspective view of the watch.

FIG. 1

FIG. 2
